UNITED STATES PATENT OFFICE.

ARTHUR A. AUST, OF BEDFORD, OHIO.

ROTARY PUMP.

1,321,585.

Specification of Letters Patent. Patented Nov. 11, 1919.

Original application filed March 1, 1917, Serial No. 151,661. Divided and this application filed September 6, 1917. Serial No. 189,980.

To all whom it may concern:

Be it known that I, ARTHUR A. AUST, a citizen of the United States, residing at Bedford, in the county of Cuyahoga and 5 State of Ohio, have invented certain new and useful Improvements in Rotary Pumps, of which the following is a specification.

My invention relates to pumps of the circular or rotary type. Pumps of this character may be used in connection with internal combustion engines as described in 10 my prior application Serial No. 151,661, filed March 1, 1917, of which this case is a division.

15 The object of my invention is to produce a pump which is simple and efficient in operation, and which can be converted into a motor by simply adjusting the parts. The pump chamber is provided with a rotatable 20 ring operated by two rotating pistons. The relation between the ring and the pistons is such that power is applied to the end of the piston rods thereby securing maximum efficiency. The ring is tangent to the inner 25 surface of the chamber and always engages the point of tangency. The piston rods are eccentric in relation to the movement of the ring and in rotating presses against the inner surface of the chamber. The chamber 30 is provided with suitable openings for admitting and expelling the water.

Other details will be pointed out in the description to follow. My invention is illustrated in the accompanying drawings, 35 wherein:

Figure 1 is an end sectional view of the pump mechanism.

Fig. 2 is a section showing the details of the pump mechanism with the pistons in 40 alinement.

Fig. 3 is a section on the line 18—18 of Fig. 2.

Fig. 4 is a detail of one of the pump pistons.

45 Fig. 5 is a detail showing a modified form of piston.

Referring to the drawings, the main shaft 320 carries the collar 310 which is fastened to the rod 312, one end of which is threaded 50 into the collar as shown in Fig. 4. The opposite end of this rod 312 carries the piston 333 at X, which in rotating presses against the walls and inner circumference of the cylinder or chamber. During this rotation 55 the piston 333 carries with it the movable

ring 321. This ring is provided with the roller bearings 322 which rest upon or engage the periphery of the flange 336.

The ring 321 is centered eccentrically in relation to the shaft and is provided with 60 an extension or ring-shaped section 337 through which the rod 312 passes. Within the ring 337 is mounted a rotatable split ring 330. This ring 330 is arranged to rotate in order to take up the variation of the 65 piston 333, which as stated is eccentric in relation to the center of the ring 321.

The rings 330 and 337 are shouldered down to reduce friction. The opening 331 in the ring 337 through which the rod 312 70 passes is provided with enough clearance to permit the eccentric movement of the piston 333 and the corresponding movement of the arm 312. As the ring rotates the piston 333 slides back and forth through the 75 close fitting opening 332 in the ring 330.

It will be noted that the piston 333 designated as X is mounted upon and keyed to the shaft 320. The other piston 333 instead of being fastened to the shaft is mounted or 80 attached to a rider or idler arranged to turn loosely upon the shaft 320. The idler 340 shown in Fig. 3 is provided with the yokes or rings through which the shaft 320 passes. The ring or bearing to which the piston 333 85 designated as X is mounted lies between the rings 341 and 342 of the idler. From this arrangement it will be seen that the piston 333 designated as X is operated directly by the shaft 320, while the other piston 333 90 turns freely upon the shaft. The ring 321, is however, provided with two split rings or collars 330 through which both pistons pass.

With this arrangement the shaft 320 in 95 rotating carries with it the piston 333 at X which causes the ring 321 to rotate. This ring in rotating carries with it the other piston 333 which is loosely mounted upon the shaft. This arrangement is necessary as the center of the ring 321 is eccentric to 100 the center of the shaft upon which the two pistons are mounted. In view of this eccentric relation it is necessary to make allowances for the pistons to assume the positions shown in Fig. 1 when the maximum 105 volume of water lies under and between the two pistons.

Referring to Fig. 2, it will be noted that the two pistons are in line and the center of the shaft 320 is directly in line with the 110

center of the ring 321 on the vertical line 18—18. In this position the chamber is divided into two equal parts and the volume of water in each part is the same.

5 In passing from this position to the position shown in Fig. 1, the volume of water increases below and between the two pistons. In order to take care of this contingency the leaf valves shown in Figs. 2 10 and 4 are provided. In assuming the position shown in Fig. 1, the valve 316 of the piston 333 to the right of Fig. 1 is caused to open due to the tendency of a vacuum to be formed between the two pistons and 15 the lower portion of the chamber. The opening of this valve allows water to pass into the space between the two pistons thus automatically compensating for the variation in position of the pistons.

20 Fig. 1 shows the pistons in their maximum eccentricity as to alinement. When the pistons start to pass from this position to assume the position shown in Fig. 2, the lower space between the pistons gradually decreases whereupon the valve 316 of the piston 333 designated as X opens and allows the water to flow into the upper partition of the chamber. The groove at I allows last of water to escape through exhaust port 351.

25 From the foregoing description it will be noted that the pistons assume varying positions but the valves 316 compensate for the varying space between the pistons.

30 The foregoing description in connection 35 with the pump shows that the water is drawn in through the intake port 350 and then forced through the exhaust port 351. In order to convert the pump to a water motor it is only necessary to force water under pressure and use the opening 351 as an intake and the opening 350 as an exhaust. Instead of reversing the intakes and exhausts the valves 316 can be reversed and the opening 350 used as an intake and the opening 351 as the exhaust.

35 From the foregoing it will be noted that the device shown in Figs. 1, 2 and 3 can be used as a pump or as a water motor at will, or a compressed air motor-meter-measuring 40 pump.

45 Having thus described my invention what I desire to secure by Letters Patent is:

1. In a machine, the combination of a 50 chamber, two rotatable pistons adapted to rotate within said chamber, means for causing said pistons to assume varying positions within said chamber during their rotation, a valve for each piston, said valves serving to compensate for the varying positions assumed by said pistons.

60 2. In a machine, the combination of a 55 compartment provided with a rotatable ring and two rotatable pistons, said ring being centered eccentrically in relation to said pis-

tons, said pistons during their rotation assuming varying positions, each of said pistons being provided with a valve, said valves serving to compensate for the varying positions assumed during their rotation.

65 3. In a machine, the combination of a 60 compartment provided with a rotatable ring and two rotatable pistons, the center of said ring being eccentric with the center of rotation of said pistons, two rotatable collars carried by said ring through which said pistons pass, means for rotating said ring and pistons, said collars serving to compensate for the varying positions which the pistons assume in relation to said ring, a valve for 70 each of said pistons, said valves serving to 75 compensate for the varying positions assumed by said pistons in relation to said compartment.

75 4. In a machine, the combination of a 80 chamber provided with a rotatable ring, of two pistons for causing the rotation of said ring, said pistons during their rotation being arranged to assume varying positions in relation to one another, each of said pistons being provided with a valve, an intake and 85 an exhaust port for said chamber, means controlled by said pistons during their rotation for drawing in a volume of material through said intake port and forcing the 90 material through said exhaust port, said valve serving to compensate for the varying 95 position assumed by said pistons during their rotation.

5. In a machine, the combination of a 100 chamber provided with a rotatable ring, of two pistons for causing rotation of said ring, said pistons and ring serving to divide the chamber into two portions, said pistons during their rotation serving to vary the area of the two portions in relation to one 105 another, means controlled by said pistons for drawing in a volume of material into each of said portions, a valve associated with each of said pistons, means controlled by said valves for compensating for the varying 110 amounts of material held in said portions during the rotation of said pistons.

6. In a machine, the combination of a 115 chamber, a plurality of rotatable pistons adapted to rotate within said chamber, said pistons serving to divide the chamber into separate portions, said pistons during their rotation serving to vary the area of the portions in relation to one another, means associated with each of said pistons for compensating for the varying area of said portions.

7. In a machine, the combination of a 120 chamber provided with a plurality of rotatable pistons, said pistons serving to divide the chamber into separate portions, said pistons during their rotation serving to vary the area of the portions of the chamber

- in relation to one another, means controlled by said pistons for drawing in a volume of material into each of said portions, means associated with each of said pistons for compensating for the varying amounts of material held in said portions during the rotation of said pistons. 5
8. In a machine, the combination of a chamber provided with a rotatable ring, a plurality of pistons rotatable with said ring, said pistons during their rotation being arranged to assume varying positions in relation to one another, an intake and exhaust port for said chamber, means controlled by 10 said pistons during their rotation for drawing in a volume of material through said intake port and forcing the material through said exhaust port, means associated with each of said pistons to compensate for 15 the varying amount of material between said pistons during their rotation. 20
9. In a machine, the combination of a chamber, a plurality of rotatable pistons within said chamber, said pistons serving to divide the chamber into separate portions, said pistons during their rotation serving to vary the area of the portions of the chamber in relation to one another, means controlled by said pistons for drawing in a volume of material into each of said portions, 25 means associated with each of said pistons for allowing the intermixing of material in said portions to compensate for the varying positions of the pistons during their rotation. 30
- 35

In testimony whereof I affix my signature.

ARTHUR A. AUST.
